UNITED STATES PATENT OFFICE.

EMERSON E. GORE, OF PHOENIX, OREGON.

IMPROVEMENT IN GANG-PLOWS.

Specification forming part of Letters Patent No. **98,370**, dated December 28, 1869.

To all whom it may concern:

Be it known that I, E. E. GORE, of Phoenix, in the county of Jackson and State of Oregon, have invented new and useful Improvement in Gang-Plows; and I do hereby declare that the following is a full, clear, and exact description, which will enable others skilled in the art to make and use the same, reference being had to the accompanying drawings, forming part of this specification.

This invention relates to improvements in gang-plows; and it consists in the construction and arrangement of parts, as hereinafter specified.

Figure 1 represents a side elevation of my improved gang-plow with some parts broken out. Fig. 2 represents a plan view, and Fig. 3 represents a front elevation.

Similar letters of reference indicate corresponding parts.

A represents a rectangular frame, supported on the front axle, B, by means of the jointed bars C and levers D, pivoted to the said bars and to the fixed studs E and provided with spring-latches F, which, engaging in the notches of the curved bars G, which support the seat, hold the said frame A higher or lower on the axles, according to the position of the notches in which the said spring-latches are engaged. The pivot-connections of the levers D with the bars C and studs E are adjustable. The frame A is provided with the diagonal brace-rods H I, connected to it near the front end and passing through the axle horizontally, to prevent longitudinal vibration of the frame on the axle. The bar H is jointed at K, to permit the axle to be turned relatively to the frame, and the bar I is provided with an extensible joint, M, whereby it may be lengthened or shortened for the purpose of varying the draft of the plows for cutting wider or narrower furrows. A rod, J, is also provided to prevent lateral motion of the frame on the axle. The rear end of the frame is supported on the spindle N of a caster-wheel, O, and a lever, P, pivoted to a stand, Q, having a jointed connection with the frame. The spindle is swiveled to the lever to permit the caster-wheel to turn freely, and the long arm of the lever is provided, near the front end, with a spring-latch, R, for engaging with notches in the rear bar or support of the seat, to hold the frame

higher or lower, which is effected by the movement of the lever up or down, the end P' being controlled by its support on the top of the spindle N. This frame A is made wider or narrower, according to the number of plows to be used in the gang, and another frame, A', is provided within the frame A for the support of the plows B', and arranged for supporting the plows in the working position, or for raising and supporting them above the ground. It is jointed near the front end, at C', to the arms D' of a transverse crank-shaft, E', and at the rear to the cranks F', journaled in the frame at G', and slotted at the other ends, where the pivot-pins H' are received. These slots prevent any binding between the front and rear crank-arms, which might occur without them if there should happen to be any difference in the length of the cranks, or if the connections of the front and rear cranks should not happen to be exactly the required distances apart. The crank I' of the shaft E' is connected by the link K' to the bent arm L' of a lever, M', pivoted at N' to a stand rising from the frame. This lever is so arranged that when the plow-supporting frame is down it will stand in a vertical position, and when it is turned down backward it draws the crank I' forward and raises the frame A' and plows out of the ground. It will be seen that the draft of the plows comes jointly on the arms D' and F' (by which the inner frame, A', is connected with the outer or larger frame, A) and the lugs R'. The pivotal connection between the arms and frame A is at the lower or under side of the latter, and at or near the upper side of A', and the stops R' prevent the inner frame falling below the level of the outer at any time, and hence, also, both sets of arms from falling to a horizontal line. Thus, when draft is applied, this inclined position of the arms D' prevents the plows rising from any cause. The arrangement of the frame A' in the frame A is such that when the plows are down in the working position the force of the draft is taken on the frame A by the bearing of the rear end of the frame A' against the cross-beam of the frame A.

O' is a spring-catch pivoted to the foot-stand P' and provided with a foot-treadle, Q'. It is so arranged that when the frame A' is raised

it will catch behind one of the lugs R' and hold the said frame up until released by the operator pressing upon the treadle with his foot. The lugs R' are placed on the frame A' so as to project over the beams of the frame A, and thereby support the said frame A' on the frame A. Opposite the ends of the frame A', when down, are placed plates S', of metal, on which the lugs R' rest, and which extend down the sides of the beams and form bearings for vertical extension of the said lugs, which work snugly between them and prevent lateral movement of the frame A' in the other. They also prevent the lugs R' from wearing the beams, as they would do if the metallic plates were not interposed, and, by reason of the vertical extension of the lugs, the requisite spaces for the arms D' F' are maintained between the beams of the two frames.

It will be seen that the frame A may be readily raised or turned on the wheels for varying the depth of the plowing; also, that each end may be varied independently of the other, as may sometimes be required.

The caster-wheel may be arranged to run in the furrow or on the "land" as preferred. The wheel working in the furrow is made larger than the other, as is customary in such plows.

In order to admit of the off horse traveling freely in the furrow, I make the landside-hound a' very narrow, and the other, a^2 , much wider, whereby the position of the tongue b^2 is more toward the land than it would be if the hounds were of equal breadth, and gives the off horse more freedom.

Having thus described my invention, I claim as new and desire to secure by Letters Patent—

1. The combination of the stops R' R' with the frames A and A' and arms D' and F', whereby the latter are retained in an inclined position, and the plows thereby prevented from rising or falling, substantially as and for the purpose specified.

2. The links D' F', connecting the frames A A', the hind links being slotted for the purpose of allowing the plows to be raised in an inclined direction, as specified.

3. The hoisting-lever M', link K', and crank I', in combination with the links D' F' and frames A A' of a gang-plow, as specified.

4. The spring-catch O', pivoted to the frame A, for the purpose of locking the frame A' in its elevated position, as specified.

5. The frame A, supported on the front axle by the rods C, and on the swiveled easter-wheel O, substantially as described, so that it can be raised and lowered at will, to adjust the position of either plow, or of both, substantially as specified.

6. The levers D, connected separately with the axle and with the frame A, for raising or lowering the latter, as specified.

7. The lever P, connected with the swiveled shank N of the easter-wheel O, and pivoted to a jointed arm, Q, that projects from the frame A, to adjust the latter, substantially as herein shown and described.

8. The combination, with the frame A and axle B, of the jointed rod H, adjustable rod I, and jointed rod J, substantially as specified.

EMERSON E. GORE.
